UNITED STATES PATENT OFFICE.

WILLIAM J. LEYER, OF ERIE, PENNSYLVANIA.

METAL-HOLDING APPARATUS FOR FLAT-BED LITHOGRAPHIC-PRINTING PRESSES.

SPECIFICATION forming part of Letters Patent No. 748,871, dated January 5, 1904.

Application filed December 1, 1902. Serial No. 133,444. (No model.)

To all whom it may concern:

Be it known that I, WILLIAM J. LEYER, a citizen of the United States, residing at Erie, in the county of Erie and State of Pennsylvania, have invented new and useful Improvements in Metal-Holding Apparatuses for Flat-Bed Lithographic-Printing Presses, of which the following is a specification.

This invention relates to metal-plate-holding apparatuses for flat-bed lithographic printing presses; and it consists in certain improvements in the construction thereof, as will be hereinafter fully described, and pointed out in the claims.

Heretofore great difficulty has been experienced in utilizing zinc or aluminium plates on flat-bed lithographic presses. The leading object of my invention is to provide an apparatus by means of which such plate may be used in such a press.

The invention is illustrated in the accompanying drawings, as follows:

Figure 1 shows a plan view of the device; Fig. 2, a section on the line 2 2 in Fig. 1; Fig. 3, an elevation of the device from the right of Fig. 1. Fig. 4 is an end elevation of the device.

A marks the metallic plate, ordinarily a zinc or aluminium plate; B, the bed. The bed is provided with the plane surface, which forms a backing for the plate. The ends of the bed are rounded at b, so as to relieve the plate at the angle as it is drawn over the corner. A clamp C, formed of the jaws C' and C'', is secured to the bed. The jaw-surfaces c c adjacent to the bed-surface are arranged at an angle to the plane of the bed-surfaces and approximately in line with the plate as it is drawn over the corner b in order to relieve the plate from a sharp bend at the edge of the clamp. By this means a much greater strain may be put upon the plate without breaking it. The clamp is provided with the clamping-screws C³, and the clamp is secured to the bed by the screws C⁴.

A sliding frame D is arranged at the opposite end of the bed B. It has the dovetail guides d, which travel in the grooves b'. Adjusting-screws d' extend through the frame into contact with the shoulder b² of the bed. There are preferably two of these adjusting-screws—one at each end—and the guides d

are so loosely fitted in the groove d' as to permit one end of the frame to be moved to a greater extent than the other for purposes hereinafter described. A bolt d² is secured to the shoulder b² and extends through the frame D. A nut d³ is arranged on the bolt d² and against the frame D. The purpose of this bolt is to make a convenient means for returning the frame to its inner position and also for locking the adjustment formed by the screws d' d'. This is accomplished by setting the nut d³ after an adjustment has been made by the screws d' d'.

The clamp E is carried by the frame D. It comprises the jaws E' E² and clamping-bolt E³. The clamping-surfaces e are arranged at an angle to the surfaces of the bed B for the purposes described in relation to the clamp C. The clamp is secured to the frame D by screws E⁴.

After a plate is secured in the clamps C and E the clamps are secured to the bed and frame, and thus the frame D is moved outwardly through the action of the screws d' d' until the plate is subjected to sufficient strain to flatten it. If it is necessary to move one side of the frame D more than the other in order to flatten the plate, this may be accomplished by the means heretofore described—namely, the screws d' d'. The bed is set in the press preferably in a manner ordinarily used with lithographic stones. It accomplishes the purposes of a lithographic stone. The initial cost is very much less. The cost of the plate is such that it is feasible to store the plates, so that copies may be struck off, as desired, while the cost and bulk of the stone is such that this is not practical.

It will be noted that the jaws extend across the plate, thus assuring an even strain on the different portions of the plate.

What I claim as new is—

1. In a metal-plate-holding apparatus for flat-bed lithographic presses the combination of a bed having a surface; clamps arranged below the plane of said surface; and means for moving one of said clamps to strain the plate and for moving one side of said clamp to a greater extent than the other.

2. In a metal-plate-holding apparatus for flat-bed photolithographic - printing presses the combination of a bed having a plane sur-

face; clamps arranged below the plane of said surface, said clamps having their jaw-surfaces extending continuously along the edge of the plate; and means for moving one of said clamps to strain the plate and for moving one side of said clamp to a greater extent than the other.

3. In a metal-plate-holding apparatus for flat-bed lithographic presses, the combination of the bed B having a plane surface forming a backing for the plate; the clamps C and E arranged at the ends of the plate and to be opened and closed by a movement in a direction at right angles in the plane of the plate on the bed, said clamps comprising the trough-shaped jaws C' E' and the upper jaws C² E² fitting therein the plane of the faces of the jaws along the edge being in line with the plate where it enters the jaws and the clamp-bolts E³ said clamps being arranged below the surface of the bed B.

4. In a metal-plate-holding apparatus for flat-bed lithographic presses, the combination of the bed B having a plane surface thereon and the rounded corners b thereon; the movable frame D arranged to permit greater movement at one end than at the other; screws d' d' for moving said frame; the clamp C secured to said bed and the clamp 30 E secured to said movable frame, said clamps being below the surface of the bed B.

5. In a metal-plate-holding apparatus for flat-bed lithographic presses, the combination of the bed B having a plane surface thereon; the movable frame D arranged to

permit greater movement at one end than at the other; screws d' d' for moving said frame; the clamp C secured to said bed and the clamp E secured to said movable frame, said clamps being below the surface of the bed B. 40

6. In a metal-plate-holding apparatus for flat-bed lithographic presses, the combination of the bed B having a plane surface thereon; the rounded corners b thereon; the movable frame D arranged to permit greater 45 movement at one end than at the other; screws d' d' for moving said frame; the clamp C secured to said bed and the clamp E secured to said movable frame, said clamp being below the surface of the bed B; and the 50 bolt d³ for the purpose described.

7. In a metal-plate-holding apparatus for flat-bed lithographic presses, the combination of the bed B having a plane surface thereon forming a backing for the plate; the 55 shoulder b² on said bed; and grooves b' in said bed; movable frame D having the dovetail arranged to operate in the grooves b'; the adjusting-screws d' d' extending through the frame against the shoulder b²; and a clamp 60 carried by said movable frame and arranged below the surface of the bed B.

In testimony whereof I have hereunto set my hand in the presence of two subscribing witnesses.

WILLIAM J. LEYER.
